UNITED STATES PATENT OFFICE

JAMES H. RAMBO, OF FAIRFIELD, ILLINOIS, ASSIGNOR TO SEXTON MANUFACTURING COMPANY, OF FAIRFIELD, ILLINOIS, A CORPORATION OF ILLINOIS

APPAREL GARMENT

Application filed March 28, 1931. Serial No. 526,056.

This invention relates generally to apparel garments and more particularly, to a certain new and useful improvement in that class of apparel-garments known as track pants and more commonly designated as "shorts".

My invention has for its chief object the provision of a neat-fitting, inexpensive garment of closed crotch track-pants type essentially comprising side-front panels and a single back panel so constructed, dimensioned, and united as to provide fullness in the crotch and across the buttocks and at the same time eliminate rear seams.

My invention has for a further object the provision of a garment of track-pants type embodying a back panel having a bulging crotch construction and a bias cut at the sides for providing a panel fullness depending over the buttocks when the garment is on the body.

My invention has for another object the provision of a three-piece garment of track-pants type including a one-piece back panel cut with a substantial bias towards the front for providing a neat fit at the waist line with the required fullness in the seat and bottom of the garment.

My invention has for still another object the provision of an improved form of track pants garment patterned in such manner as to effect a saving both in the yardage of material used, as well as the labor required in marking, cutting, and sewing the garment.

And with the above and other objects in view, my invention resides in the novel features of form, construction, arrangement, and combination of parts hereinafter described and set forth in the claim.

In the accompanying drawing,

Figure 1 is a side front view of a garment of my invention as worn on the trunk of the body;

Figure 2 is a rear view of the garment;

Figure 3 is a front side view of the garment;

Figure 4 is the pattern of the back panel; and

Figures 5 and 6 are the patterns of the two front panels, respectively.

Referring now more in detail and by ref-

erence characters to the drawing, which illustrates a preferred embodiment of my invention, I illustrate a form of bifurcated wearing apparel commonly known as a track pants, although the garment may, and often is, employed as a nether garment for male and female wear.

The garment is constructed of and comprises three pieces or sections, that is, a single back panel A, and two side-front panels, B, C.

The back panel A is cut with its waist-edge 1 straight on the thread of the material, its opposite side edges 2 are cut approximately on a 25 degree bias towards the front, and is biased on the bottom, as at 3, from each side towards the crotch. At the crotch or inseam, the panel A is cut with a double reversed curve providing a bulge 4 at the center of the crotch curve 5, all as best seen in Figure 4, the back panel or section A having a width between the opposite meeting corners of its side and bottom edges 2 and 3 approximately equal to the width of the complete garment, when laid flat, as best seen in Figure 2.

The side-front panels B, C, are substantially similar in form and are each cut with a slight bias at the waist 6 towards the rear side seam 7, and provided at the front with a somewhat angular or oblique crotch or inseam edge 8 terminating in an approximately V-shaped indenture 9, from the inner or upper end of which the front edge is extended straightwise upwardly, as at 10, to provide material for forming fold-over front facings in the finished garment, the shape of the panels B, C, being best seen in Figures 5 and 6. Preferably, it may be added, the side-edge 7 and bottom edge 11 of each of the panels or sections B, C, are cut substantially straight with the threads of the material.

In assembling the panels A, B, and C to form the finished garment, best seen in Figures 2 and 3, the oblique side edges 2 of the back panel A are stitched or sewed to the straight side edges 7 of the panels B, C, at opposite side seams 12, and the indenture-edges 9 of the panels B, C, are sewed together at the front seam of the garment. The oblique front-edge portions 8 of the panels B, C, are

stitched to the curved crotch edge 4, 5, of the panel A at the inseam 13, thereby providing the leg-openings 14, and, as will be readily seen, the curved edge 4, 5 when conjoined to said front-edge portions 8, provide, by reason of the crotch formation of the panel A, a fullness, as at 15, in the crotch, as best seen in Figure 2.

The combined effect of the fullness 15 and 10 the bias cut of the side edges 2 of the back panel A provides, in the finished garment, a panel-fullness, as at D, depending over the buttocks, apparent, as the garment is worn, and when the body is in erect posture, as a 15 bag-like effect extending laterally in both directions from the crotch fullness 15 thence upwardly approximately to the waist line 16, as best seen in Figures 1 and 2. The fullness D provides a most adequate and comfortable 20 seat to the garment wholly without seams that might affect the comfort of the garment not, to my knowledge, to be obtained in garments of this type as heretofore constructed.

The straight front edge-portion 10 of the 25 panel C is folded over and sewed, as at 17, for forming one of the opposing margins of the front opening of the garment, the straight front-edge portion 10 of the other panel B being similarly folded over and sewed for a 30 like purpose.

I prefer also to provide a stomach band 18 at the front of the garment, the same being provided with cooperable fastening means 19 at the front opening, as shown.

The waist of the back panel A is most conveniently and comfortably gathered with an elastic band 20, as best seen in Figure 2, the gathering having the effect of emphasizing the panel fullness D.

Thus, by my invention, I am enabled to 40 provide a track-pants garment simple in construction and low in cost.

The garment is composed of only three 45 pieces, effecting a saving in yardage of material, as well as labor in the marking and cutting thereof.

The garment is completely closed in two 50 operations, that is, the sewing of one side and the inseam (the other side having been previously seamed), thus simplifying the closure operation, avoiding the possibility of errors in making the closure, and hence increasing production for a given labor cost.

The back panel A, being cut in one piece, 55 provides approximately two or three inches more seat fullness than heretofore obtained in this class of garment.

The side seams of the garment are approx- 60 imately on a 25 degree bias, which provides a substantially perfect fit at the waist line, while also providing the required fullness in the seat and bottom of the garment.

The crotch of the garment, being cut with

the reverse curve on the back panel as described, provides a bulging continuous inseam having the novel result of providing approximately from two and one half (2½) to three (3) inches more back rise than can be obtained in garments of the type described as heretofore constructed.

Thus, in every respect, the garment fulfills the objects stated, and it will be understood that changes and modifications in the form, construction, arrangement, and combination of the several parts of the garment may be made and substituted for those herein shown and described without departing from the nature and principle of my invention.

Having thus described my invention, what I claim and desire to secure by Letters Patent is,—

A garment of the track-pants type having a closed back, seat, and crotch and comprising in its construction a single back-panel and a pair of companion side-front panels, the back-panel having a greater width at its lower margin than at its upper margin and its said margins being connected by opposed downwardly and forwardly oblique side edges, the upper margin of the back-panel being straight from side edge to side edge and the bottom margin of the back-panel being of irregular shape divided to include opposed downwardly and rearwardly oblique edges and an intermediate upwardly indented crotch of undulatory contour, the back-panel being of greater height centrally than at its oblique side edges to afford extreme fullness in the crotch, each of the front-side panels having a straight rear edge and a front edge comprising an upper straight-portion, an oblique lower inseam portion, and an intermediate connecting indenture, the side-front panels being stitched along their straight rear edges to the oblique side edges of the back-panel in the formation of seams extending obliquely upwardly from the garment's lower edge at approximately the opposite sides of the garment to the garment's upper margin at points thereon spaced rearwardly from the opposite sides of the garment, the side front-panels being also at their oblique inseam edges stitched to the sinuous crotch-edge of the back-panel in the formation of leg-openings, the side-front panels being further stitched together at their said indentures in the formation of a closed crotch, each of the side-front panels along its straight front edge being folded over and stitched in the formation of companion overlapping placket-members, and, co-operable fastening members on the placket-members for detachably securing the same together in garment closing position.

In testimony whereof, I have signed my name to this specification.

JAMES H. RAMBO.
